UNITED STATES PATENT OFFICE.

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

WRINGER.

Application filed April 10, 1924. Serial No. 705,558.

To all whom it may concern:

Be it known that I, ALPHEUS W. ALTORFER, a citizen of the United States, a resident of Peoria, in the county of Peoria and State of Illinois, have invented new and useful Improvements in Wringers, of which the following is a specification.

This invention has reference to wringers, and it has for its principal object to provide a quick releasing means for the compression on the wringer rolls in the event of a person accidentally getting the fingers or hand caught between the rolls, or in the event of fine fabrics becoming entangled.

The invention has for a further object to improve and simplify the compression and releasing means described and claimed in Letters Patent 1,502,225, granted to my assignees July 22, 1924. In said patent there is disclosed duplicate coacting levers and a single control lever; whereas, in the present disclosure a single compression means, coacting means and lever control is provided, which both simplifies and lessens the cost. It is common in both disclosures to pivot the control lever so that it is moved laterally or cross-wise of the wringer frame, in either direction. This is of considerable advantage. It provides a release where the pressure applied by the attendant is a push or pull, toward or from the body, rather than a downward or sidewise movement of the arm, which is both inconvenient and allows of very little body pressure.

That the invention may be more fully understood, reference is had to the accompanying drawings, illustrating a preferred embodiment of the invention, in which:

Figure 1 is a side elevation, partly in section, showing a wringer frame and rolls and my invention embodied therein;

Figure 2 is a partial plan view of Figure 1 as the same would appear looking down on the line 2-2 in said figure, and

Figure 3 is a detail elevation of the control lever, as the same would appear on the line 3-3 Figure 1.

Like characters of reference denote corresponding parts throughout the figures.

The frame 1 of the wringer may be of suitable construction and made applicable to the swinging or stationary type, as may be desired. If of metal it is preferable to construct the same of duplicate sections, such as 2 and 3 formed at their opposite ends

with upstanding semi-spherical bodies 4 joined to form barrels in which are vertically slideable members 5 having associated with their lower ends bearing blocks 6 to receive the spindle ends 7 of an upper wringer roll 8 arranged to have a friction impinging relation with a lower wringer roll 9 provided with spindle ends 10 journaled in bearing blocks 11 supported in the lower ends of the barrels of the frame; one of said spindles 10 projects outwardly to one side and adapted to receive power from a suitable source, not shown, for operating the same. The structure shown contemplates gearless operated wringer rolls.

It is arranged to apply pressure to the slideable members 5 to retain or hold the rolls 8 and 9 in cooperative relation. Such means preferably comprises a resilient bar 12 disposed longitudinally of the wringer frame, its opposite ends bearing down on the slideable members 5. To said resilient bar 12 mediate its ends is connected a block 13 with which the lower end of a threaded rod 14 engages. Said rod is disposed in a vertical position and has a threaded relation with a bushing 15 vertically slideable in the cross-head of the wringer frame, said rod on its upper end being provided with a knurled disk 16 by means of which the rod may be screwed down to increase the spring pressure through the resilient bar to the slideable members 5, or to release such pressure, as the case may be. The bushing 15 is vertically slideable and adapted to move upward with the resilient bar 12 as I shall now explain.

In normal operative position the bushing 15 is in the position shown in Figure 1 and so held by a lever 17 fulcrumed at 18 on the cross-head of the wringer frame and disposed longitudinally thereof, one end of the lever 17 bearing down on the bushing 15, with the bar 14 adjusted to apply the desired pressure to provide the necessary compression to hold the wringer roll 8 in proper working relation with the roll 9. The opposite or outer end of said lever is held raised by a shoulder 19 formed or provided on a hand control lever 20 which is adapted to ride under and elevate said lever 17 to operative position. Said shoulder 19 has beveled ends 21 to permit it to ride easily under the outer end of the lever 17 and have a cam-like action thereon. This control lever 20

is preferably fulcrumed on an extension 22 projecting upwardly from the cross-head of the frame and at one end thereof so as to be swung laterally of or cross-wise of the wringer frame in either direction. The desirability of this will be seen at a glance. It provides for a push or pull on the control lever 20 which is a more effective operation than would result from a downward or side-wise arm movement. With the lever 20 operative in an upstanding position, as shown in Figure 1 it will be readily seen that if an arm is not available an attendant could use her head and push the lever over into a released position to free the lever 17 and permit the resilient bar to operate to release the wringer rolls. Such an arrangement is further desirable, due to the fact that an attendant may be in a position with the tub intervening so that a push or pull would be the only effective mode of actuating said control lever, and when a hand is caught or fine fabrics have become entangled quick action is desirable.

25. What I claim is:—

1. In a wringer, in combination, a wringer frame, wringer rolls journaled in said frame, a single means to apply pressure at a central point mediate the ends of said rolls resulting in impinging frictional contact between said rolls, means to hold said pressure applying means, and a control member at one end of said frame to co-act with said holding means and pivoted to the frame to be swung cross-wise thereof in either direction.

2. In a wringer, in combination, a wringer frame, wringer rolls journaled in said frame, a resilient member disposed above and longitudinally of said rolls coacting with the op-

posite ends thereof, means for adjusting the compression in said member located centrally thereof, means to hold said member in coacting relation with said rolls, and a control lever for said holding means, said lever being fulcrumed on said frame at one end thereof to be swung cross-wise thereof in either direction.

3. In a wringer, in combination, a wringer frame, wringer rolls journaled in said frame, a resilient bar disposed above and longitudinally of said rolls and arranged to apply pressure to the opposite ends thereof, a lever pivoted on said frame approximately centrally thereof and arranged to co-act with said bar to hold it in operative position, and a control lever pivoted on said frame at one end thereof to be swung cross-wise thereof in either direction, and adapted to have a cam-like action with said first mentioned lever to hold it in operative position.

4. In a wringer, in combination, a wringer frame, wringer rolls journaled in said frame, a resilient bar disposed above and longitudinally of said rolls and coacting at its opposite ends with said rolls, means arranged centrally of said bar to adjust the compression action thereof, a lever pivoted on said frame and arranged to hold said adjusting means, and a control lever pivoted on said frame at one end thereof to be moved side-wise in either direction, and provided with a beveled shoulder adapted to ride beneath said first mentioned lever to engage it and hold it in operative position.

In witness whereof, I have hereunto affixed my hand this 8th day of April, 1924.

ALPHEUS W. ALTORFER.
